JOHN V. ABRONSKI, OF PITMAN, NEW JERSEY

SCREEN

Application filed May 29, 1929. Serial No. 366,840.

The present invention relates to screens for windows and the like. The subject matter of the present application is a continuation of my application, Serial No. 213,398, filed August 16, 1927 for that part of the subject matter common to the two applications.

An object of the invention is to provide an improved connection between two relatively slidable screen sections which will be sturdy and rigid while permitting easy relative sliding between the sections.

A further object is to provide frame members for relatively slidable sections of a screen having a sturdy sliding connection, the frame members being made from single unitary strips of sheet metal bent upon themselves in an improved manner to form said sliding connection, together with means for connecting the screen cloth thereto.

20 A still further object is to provide a screen comprising relatively slidable, overlapping screen sections having an improved baffle on their overlapping edges constructed to effectively prevent the passage of insects between the sections.

25 A further object is to provide an improved screen comprising relatively slidable sections and slidable as a whole in a window frame so constructed that it will adjust itself to deformities of the window frame when sliding therein.

30 A further object is to provide a screen adapted for sliding in a window frame and having frame members with slides thereon and means for binding the screen material to the said members, all the parts of each of said members being formed in an improved manner of an integral strip of sheet metal.

35 A further object is to provide a screen having a sturdy effective improved interengaging sliding connection with a window frame.

40 A further object is to provide a window screen comprising relatively slidable sections slidably connected as a unit in a window frame, the sliding connection of which with said frame being such as to prevent any undesirable relative sliding between the sections when slidably connected with the window frame.

45 50 A further object is to provide a screen com-

posed of members each member of which is formed from one piece of metal, so shaped or formed that the assembly of said members into a screen will form a construction which is both adjustable horizontally and at the same time slidable vertically.

55 A further object is to provide a screen composed of members, each member of which is formed in an improved member from one piece of metal, so shaped or formed that when the wire screening is inserted in the frame the said screening will be drawn taut.

60 A further object is to provide a screen composed of members, each member of which is formed in an improved manner from one piece of metal, so shaped or formed that the frame will be both sturdy and rigid and without tubular or other openings or spaces.

65 The screen comprises relatively slidable sections having frame members constructed of strips of sheet metal, the top and bottom members of the two sections having an interengaging slidable connection provided by forming the top and bottom members of one section with lateral flanges and those of the other section with flanges overlapping and embracing the flanges on the first section.

70 75 This sliding connection may be further strengthened and made sturdy by providing a nesting relation between these members.

80 The frame members may be made of integral strips of sheet metal bent upon itself to form integral screen holding members, slides, flanges, shoulders and abutments, as the case may be.

85 90 The sections may also be adapted both for relative lateral adjustment and vertical sliding, as a unit window frame by providing slides and slideways on the frame and on the screen sections interengaging so as to prevent relative sliding movement of the sections.

95 Aside from the other elements of construction tending to this end, passage of flies past the screen is prevented by provision of baffles on the overlapping ends of each of the screen sections resting against the screen material of the other section.

100 For a better understanding of the inven-

tion, reference may be had to the accompanying drawings in which is illustrated an embodiment of the invention.

In the drawings:

5 Figure 1 is a fragmentary elevation of a window frame showing a screen construction made in accordance with the principles of the present invention mounted therein,

10 Figure 2 is a horizontal section on a line 2—2 of Figure 1,

Figure 3 is a vertical section through one of the screen sections on an enlarged scale compared with Figures 1 and 2,

15 Figure 4 is a similar section through the other screen section,

Figure 5 is a section on line 5—5 of Figure 1 showing the screen sections as assembled,

20 Figure 6 is a fragmentary detail on a still further enlarged scale showing one member 20 of the sliding connection between the window frame and the screen frame,

Figure 7 is a fragmentary view showing the companion sliding connection attached to one of the screen sections,

25 Figure 8 is a view similar to Figure 7 showing the sliding connection associated with the other of the screen sections,

Figure 9 shows the binding for the edge of one of the screen sections which overlaps the 30 other screen section,

Figure 10 is a similar view of the binding edge of the other screen section: both of these bindings are provided with baffles integrally formed therewith, and

35 Figure 11 is a section on the line 11—11 of Figure 2 showing the construction of one of the baffle members for accommodating the same to the frame structure.

Referring to the drawings in detail, 40 15 designates a window frame, 16 the window sill and 17 the sash of a window mounted therein. Mounted within the window frame are outer and inner screen sections 18 and 19 having relative sliding connection with each 45 other and sliding connection taking the two sections as a unit relative to the window frame.

The screen sections are comprised of screen bodies 20 and 21 and frames 22 and 23. 50 These screen frames have each a side member, as designated by the numerals 24 and 25, top members 26 and 27, bottom members 28 and 29, and bindings 30 and 31 on the overlapping edges of the screen sections.

55 The side members are provided with portions bent to interlock with members 32 secured to the side members of the window frame and extending in a vertical direction.

60 The connection between the top members 26 and 27 and the bottom members 28 and 29 by which relative lateral adjustment is provided between the screen sections is clearly illustrated in Figures 3, 4 and 5 of the drawings, Figures 3 and 4 showing the two sec-

tions separate and Figure 5 showing the sections as assembled.

Both the top and bottom frame members of each section consist of strips of sheet metal bent upon themselves to provide clamping members and respectively, slides and slide-ways.

Referring specifically to Figure 3, this strip of metal is bent to form a body portion 33 having a lateral flange 34 formed on one edge 75 constituting a slide. The body portion is bent along the opposite edge in the same direction as the flange 34 to form a flange 35, the metal being rebent upon itself in parallelism with said last named flange and then in parallelism with the body portion forming an edge 80 in contact with the flange 34 where the metal is again bent to form a clamping member 36 having a portion lying in parallelism with the flange 35 and a portion 37 overlapping the free edge of the flange 35 and folded back between the said edge and the portion 37, as clearly shown; that last fold being made for purposes of strength and to avoid the exposure of a raw edge. The top and the bottom frame members of this section are identical in construction, as clearly shown in Figure 3 of the drawings.

Referring now to Figure 4, showing the other section of the screen, a similar construction is provided for the top and bottom members having a body portion 38 which is provided at one edge with a flange 39 extending laterally therefrom, said flange having a rebent portion 40 providing a hook construction 100 considering the cross-sectional showing in Figure 4, the portion 40 being spaced from the flange 39 a sufficient distance to receive the edge of the flange 34 therebetween and to provide a slideway for said flange 34.

105 The body portion is provided on its other edge with a flange 41 extending in the same direction as the flange 39 and rebent upon and in parallelism with itself, extending then along the body portion and being rebent adjacent the flange 39 to provide a clamping member 42 which extends first in parallelism with the body portion 38 then upwardly in parallelism with the flange 41 and overlapping the end of the same, as at 43, in a similar manner 110 to the member 37 shown in Figure 3.

The top and bottom frame members of the section shown in Figure 3 are of a cross-sectional configuration to be received snugly in the recess formed between flange 39 and the portion of the clamping member 42 parallel to flange 41 in the top and bottom frame members of the section shown in Figure 4. The assembly of these two sections in this manner is clearly illustrated in Figure 5 of the drawings and by this construction a sturdy sliding connection is provided between the two screen sections inseparable except by a relative sliding movement of the sections in the intended manner.

It will be understood that, while the fit between these members is intentionally snug to prevent the passage of insects and to provide against rattle and other annoyances, in the nature of things there will be a slight play between the sections sufficient to provide for adjustment of the screen sections relative to each other to compensate for any usual deformity of the window frame in which the screen is mounted.

The screen is preferably constructed so as to allow an interlocking sliding connection with the members 32 secured to the sides of the window frame. This interlocking sliding connection is shown in Figure 2 of the drawings and the details of construction are shown in Figures 6, 7 and 8 of the drawings.

Figure 6 shows the member 32 which consists of a body member 44 bent upon itself for purposes of strength and to conceal the raw edge 45 and having formed on its other edge a hook-shaped slideway 46 adapted to engage with a similar member 47 hook-shaped in cross-section and formed on one edge of the body portion 48 of one of the side frame members of the screen.

Figure 7 shows the side frame member 24 and Figure 8 the side frame member 25. The side frame members have formed on the edges of the body portions 48 opposite to the hooked member 47 flanges 49 extending at right angles to the body portion and formed by rebending the sheet metal upon itself, then in parallelism to the body portion into abutment with the shoulders 50 provided by the hook members, and thence transversely in parallelism with the body member again to form clamping members or shields 51 which then extend in parallelism to the flanges 49 providing a lip 52 overlapping the edges of the flanges.

The two side frame members differ from each other merely in the detail of the extent of the flange 49 and the associated portion of the clamping member 51, as will be clearly seen by an observance of Figures 7 and 8 and the purpose of this arrangement will be apparent by an examination of Figure 2 of the drawings.

The binding of the overlapping edges of the screen sections is illustrated in Figure 2 of the drawings and in an enlarged detail in Figures 9 and 10. The bindings 30 and 31 are both constructed of strips of sheet metal folded upon themselves providing a body portion 53 having a flange extending laterally therefrom at one edge, as shown at 54, and a clamping portion 55 extending from the other edge in parallelism with the body portion and then into parallelism with the flange 54, the same extending over the edge of the flange, as at 56.

The portion 56 has a bead 57 formed thereon in the construction as shown in Figure 9 of the drawings and this bead or flange 57

constitutes a baffle designed to rest against the screen material of the opposite screen section. The metal of the flange 54 and of the member 55 are both turned in, as clearly shown in Figure 9 of the drawings to conceal the raw edges of the material.

The construction as illustrated in Figure 10 shows a similar bead or flange 58 constructed at the meeting of the body portion 53 and the clamping member 55. This member 58 also constitutes a baffle to prevent the ingress of insects into the space 59 between the two screen sections. The two baffles 57 and 58 constitute a double guard against the passage of flies or other insects from the outside of a building to the interior thereof.

Figure 11 shows a detail of one of the baffle members, the view being taken on line 11—11 of Figure 2 of the drawings, and illustrates the manner in which this baffle member is cut away, as at 60, to accommodate the same to the portions 43 of the top and bottom frame members of the section 18.

The screen construction herein described and shown provides that each frame member in all of its parts is integrally formed from a single strip of sheet material so bent upon itself as to give rigidity and strength without resorting to the provision of tubular beads and other similar devices for strengthening the construction thereof, all of the parts of each of the frame members being formed by bendings made in the material of a single strip of sheet metal. A sturdy connection between the relatively slidable screen sections has thus been provided which lends strength to the connection and facilitates the sliding of one section upon the other to adjust the screen to the size of the window to be fitted.

These screen sections are also provided with an interlocking or interengaging connection with slideways mounted in the window frame of a character that will prevent the accidental collapsing of the screen sections and their dropping out of the window to the ground below.

The construction also lends itself to adjustment of the screen sections to deformities in the window frame due to settling of the building or otherwise and provides an insect-tight connection between the screen sections and between the screen sections and the surrounding window frame.

It will be understood, of course, that various changes may be made in the construction herein set forth within the purview of the invention as herein described and hereinafter claimed.

I claim:

1. In a frame adapted to support a screen cloth, a frame member formed from a single strip of material and including a body part, a flange along one edge of the body part, a clamping part formed on the other edge of the body part, a baffle formed at right angles

on the clamping part, and a lip on the baffle adapted to overlie the edge of the flange.

2. In a frame adapted to support a screen cloth, a frame member formed from a single strip, including a double thick flange formed by folding one edge of the strip and bending it in one direction, a lip formed by bending the other edge of the strip in the same direction, a baffle formed by bending the strip

5 in the opposite direction, a body part and a clamping part formed by folding the strip whereby the screen cloth may be drawn over the flange and clamped between the baffle and the flange and be abutted by the baffle
10 and lip.

3. In a frame a member comprising a single sheet folded to form a ledge having an infolded fabric supporting edge and again folded to form a strip having an infolded edge coacting with and clamped in relation to the ledge.

4. In a frame a member comprising a single sheet folded to form a ledge having an infolded fabric supporting edge and again folded to form a strip having an infolded edge coacting with and clamped in relation to the ledge, and intermediate folds including a clamping section alongside and clamped relative to the side of the ledge.

25 5. In a frame a member comprising a single sheet folded to form a ledge having an infolded fabric supporting edge and again folded to form a strip having an infolded edge coacting with and clamped in relation to the ledge, and a flange extending laterally from said clamping section.

6. In a frame a member comprising a single sheet folded to form a ledge having an infolded fabric supporting edge and again folded to form a strip having an infolded edge coacting with and clamped in relation to the ledge, a flange extending laterally from said clamping section, and a return bend formed at the lateral edge of the flange.

45 7. In a frame a member comprising a single sheet folded to form a ledge having an infolded fabric supporting edge and again folded to form a strip having an infolded edge coacting with and clamped in relation to the ledge, a flange extending laterally from said clamping section, a return bend formed at the edge of the flange and lying within the opposite planes of the flange.

8. In a frame a member comprising a single sheet folded to form a ledge having an infolded fabric supporting edge and again folded to form a strip having an infolded edge coacting with and clamped in relation to the ledge, and a folded bead upstanding from the strip.

55 9. In a frame a member comprising a single sheet folded to form a ledge having an infolded fabric supporting edge and again folded to form a strip having an infolded edge coacting with and clamped in relation to the ledge, a flange extending laterally from

to the ledge, and intermediate folds including a clamping section lying alongside and clamped relative to the side of the ledge, and a flange extending laterally from said clamping sections.

70 10. In a frame a member comprising a single sheet folded to form a ledge having an infolded fabric supporting edge and again folded to form a strip having an infolded edge coacting with and clamped in relation to the ledge, a folded bead upstanding from the strip and intermediate folds including a clamping section lying alongside and clamped relative to the side of the ledge, a flange extending laterally from said clamping section, a return bend formed at the lateral edge of the flange and lying within the opposite planes of the flange, and a section interlying 75 the flange and return bend.

80 11. In a frame a member comprising a single sheet folded to form a ledge having an infolded fabric supporting edge and again folded to form a strip having an infolded edge coacting with and clamped in relation to the ledge, and a slide member having a return bend coacting with the folded part remote from the ledge.

85 12. In a frame a member comprising a single sheet folded to form a ledge having an infolded fabric supporting edge and again folded to form a strip having an infolded edge coacting with and clamped in relation to the ledge, intermediate folds including a clamping section alongside and clamped relative to the side of the ledge, and a slide member having a return bend coacting with the folded part remote from the ledge.

90 13. In a frame a member comprising a single sheet folded to form a ledge having an infolded fabric supporting edge and again folded to form a strip having an infolded edge coacting with and clamped in relation to the ledge, a flange extending laterally from said clamping section, and a slide member having a return bend coacting with the folded part remote from the ledge.

95 14. In a frame a member comprising a single sheet folded to form a ledge having an infolded fabric supporting edge and again folded to form a strip having an infolded edge coacting with and clamped in relation to the ledge, a flange extending laterally from said clamping section, a return bend formed at the lateral edge of the flange, and a slide member having a return bend coacting with the folded part remote from the ledge.

100 15. In a frame a member comprising a single sheet folded to form a ledge having an infolded fabric supporting edge and again folded to form a strip having an infolded edge coacting with and clamped in relation to the ledge, a flange extending laterally from said clamping section, a return bend formed at the edge of the flange and lying within the opposite planes of the flange, and a slide 105 member having a return bend coacting with the folded part remote from the ledge.

110 16. In a frame a member comprising a single sheet folded to form a ledge having an infolded fabric supporting edge and again folded to form a strip having an infolded edge coacting with and clamped in relation to the ledge, a flange extending laterally from

115 said clamping section, a return bend formed at the edge of the flange and lying within the opposite planes of the flange, and a slide 120 member having a return bend coacting with the folded part remote from the ledge.

125 17. In a frame a member comprising a single sheet folded to form a ledge having an infolded fabric supporting edge and again folded to form a strip having an infolded edge coacting with and clamped in relation to the ledge, a flange extending laterally from

130 said clamping section, a return bend formed at the edge of the flange and lying within the opposite planes of the flange, and a slide member having a return bend coacting with the folded part remote from the ledge.

member having a return bend coacting with the folded part remote from the ledge.

16. In a frame a member comprising a single sheet folded to form a ledge having an infolded fabric supporting edge and again folded to form a strip having an infolded edge coacting with and clamped in relation to the ledge, a folded bead upstanding from the strip, and a slide member having a return bend coacting with the folded part remote from the ledge.

17. In a frame a member comprising a single sheet folded to form a ledge having an infolded fabric supporting edge and again folded to form a strip having an infolded edge coacting with and clamped in relation to the ledge, intermediate folds including a clamping section lying alongside and clamped relative to the side of the ledge, a flange extending laterally from said clamping sections, and a slide member having a return bend coacting with the folded part remote from the ledge.

18. In a frame a member comprising a single sheet folded to form a ledge having an infolded fabric supporting edge and again folded to form a strip having an infolded edge coacting with and clamped in relation to the ledge, a folded bead upstanding from the strip, intermediate folds including a clamping section lying alongside and clamped relative to the side of the ledge, a flange extending laterally from said clamping section, a return bend formed at the lateral edge of the flange and lying within the opposite planes of the flange, a section interlying the flange and return bend, and a slide member having a return bend coacting with the folded part remote from the ledge.

19. A screen comprising a panel having a frame section embodying a web lying in some of the major planes of the panel, a fabric supporting ledge upstanding from the web, a flange upstanding from the web, said flanges forming a sliding part for coaction with a complementary guide strip.

20. A screen comprising a panel having a frame section embodying a web lying in some of the major planes of the panel, a fabric supporting ledge upstanding from one edge of the web, a flange upstanding from the web at the edge opposite the bead.

21. A screen comprising a panel having a frame section embodying a web lying in some of the major planes of the panel, a fabric supporting ledge upstanding from one edge of the web, a flange upstanding from the web, a return bend formed on the flange, said flanges forming a sliding part for coaction with the complementary guide strip.

22. A screen comprising a panel having a frame section embodying a web lying in some of the major planes of the panel, a fabric supporting ledge upstanding from one edge of the web, a flange upstanding from the web,

a return bend formed on the flange and directed toward the ledge, said flange forming a sliding part for coaction with a complementary guide strip.

23. A screen comprising a panel having a frame section embodying a web lying in some of the major planes of the panel, a fabric supporting ledge upstanding from one edge of the web, a flange upstanding from the web at the edge opposite the bead, a second panel having a frame section fitting between and slidably coacting with the ledge and embodying a return bend.

24. A screen comprising a panel having a frame section embodying a web lying in some of the major planes of the panel, a fabric supporting ledge upstanding from one edge of the web, a flange upstanding from the web at the edge opposite the bead, a second panel having a frame section fitting between and slidably coacting with the ledge and return bend, said frame section embodying a ledge formed to support a fabric overlying the ledge of the first panel.

25. A screen comprising a panel having a frame section embodying a web lying in some of the major planes of the panel, a fabric supporting ledge upstanding from one edge of the web, a flange upstanding from the web at the edge opposite the bead, a return bend formed on the ledge, a second panel having a frame section fitting between and slidably coacting with the ledge and return bend, said frame section embodying a ledge formed to support a fabric overlying the ledge of the first panel, said flanges forming a sliding part for coaction with a complementary guide strip.

In testimony whereof I have signed my name to this specification.

JOHN V. ABRONSKI.
